UNITED STATES PATENT OFFICE.

ALBERT FENIMORE ROCKWELL, OF NEW BRITAIN, CONNECTICUT, ASSIGNOR
TO THE NEW DEPARTURE BELL COMPANY, OF BRISTOL, CONNECTICUT.

DESIGN FOR A BICYCLE-BELL CLAMP.

SPECIFICATION forming part of Design No. 32,201, dated February 6, 1900.

Application filed October 28, 1899. Serial No. 735,132. Term of patent 7 years.

To all whom it may concern:

Be it known that I, ALBERT FENIMORE ROCKWELL, of New Britain, in the county of Hartford and State of Connecticut, have invented a new and original Design for a Bicycle-Bell Clamp; and I do hereby declare the following to be a full, clear, and exact description of the invention, such as will enable others skilled in the art to which it appertains to make and use the same.

Reference is made to the accompanying drawings, which form a part of this specification.

This invention relates to a design for a clamp for a bicycle-bell; and it consists in such a clamp having the shape and configuration substantially as shown in the accompanying drawings, in which—

Figure 1 is a side view of the clamp which embodies this design. Fig. 2 is a plan view of the same. Fig. 3 is one end view of the same, and Fig. 4 is the other or opposite end view of the same.

It will be observed that this design consists in the bent or curved body of the clamp, (denoted by letter B,) with one side cut out into curvilinear shape complementary of the shape of the handle-bar, and the circular band A,

all conforming to the circular shape of the ordinary bicycle handle-bar. As seen in side 30 view, we have the body or box with the end shaped to receive the handle-bar and the circular band-clamp. As seen in the plan view, we have the box (denoted by the letter B) and the circular band-clamp in perspective. The 35 same appear in slightly-different aspects, as shown in Figs. 3 and 4, the one denoting one end view of the bicycle-bell clamp and the other denoting the other view of the clamp.

The essential feature of this design is the 40 body or box composed of a curved box with one end cut out in curvilinear contour, with the circular band substantially over the center and fitting the curved box.

What is claimed, and what is desired to be 45 secured by Letters Patent, is—

The design for a bicycle-bell clamp, substantially as shown and described.

In testimony whereof I have signed this specification in the presence of two subscribing 50 witnesses.

ALBERT FENIMORE ROCKWELL.

In presence of—

LAURA B. PENFIELD,
ALICE E. BROWN.
